CARTON

Wayne Pfundstein and Odell Wilson, Chicago, Ill.

Application October 26, 1938, Serial No. 236,994

2 Claims. (Cl. 229—37)

Our invention relates to a carton made of cardboard or the like for holding popcorn, salads, and a number of other commodities.

Among the objects of our invention is to create a carton having reinforced portions and therefore greater strength; to provide a carton adapted to stand upright without the need of extraneous devices; to supply a carton which is substantially leakproof and particularly adapted for semiwet foods such as salads; to create a carton in which no glue is needed for the top or bottom and which has members that are adapted to snap into place and remain in position, and such other objects and advantages and capabilities as will later more fully appear and which are inherently possessed by our invention.

While we have disclosed herein preferred embodiments of our invention, yet we wish it understood that the same are merely illustrative and are susceptible of modification and change without departing from the spirit of our invention.

Referring to the drawings, Fig. 1 is a plan view of a blank for our carton with an open top; Fig. 2 is an edge view illustrating the rib in folded position; Fig. 3 is a plan view partially in perspective illustrating the first steps in the folding of our blank to form our carton; Fig. 4 is a detail view illustrating the interfolding of the rib portions; Fig. 5 is a plan view of the form in which our carton is delivered to prospective users; Fig. 6 illustrates the position of our carton when the first of the four flaps has been folded into position; Figs. 7, 8 and 9 show the folding of the second, third and fourth flaps in position; Fig. 10 is a detail view of the end of the carton with the last flap about to be snapped into position; Fig. 11 is a plan view of a blank for our carton having both closed bottom and top.

Referring more particularly to the embodiments selected to illustrate our invention, it comprises a blank 10 substantially rectangular in shape. An interrupted lateral score 11 extends across the face of blank 10. Another lateral score 12 spaced a short distance below score 11 extends across the under-side of the blank 10 and folds outwardly forming a rib or fold 13. A plurality of spaced longitudinal scores 14, 15, 16 and 17 extend from the upper end of the blank 10 and end slightly short of score 11 forming sections 18, 19, 20, 21 and 22. Since longitudinal scores 14, 15, 16 and 17 do not meet or cross lateral score 11 the portions 23, 24, 25 and 26, where these scores would meet if continued,

are unweakened at points of unusual wear and therefore are stronger and leak proof. When the blank is later folded inwardly on scores 14, 15, 16 and 17 sections 27, 28, 29, 30 and 31 are formed in the rib 13. Extending longitudinally from score 12 are spaced slits 32, 33, 34 and 35 continuing on down to the lower end of the blank 10. Said slits 32, 33, 34 and 35 form sections 36, 37, 38, 39 and 40. Slit 32 is cut out of the inner side edge of section 36. Slits 33 and 34 are cut out of opposite side edges of section 38. Slit 35 is cut out of the inner side edge of section 40. Sections 37 and 39 are not cut away and remain at their full original size.

In forming our carton the blank 10 is bent inwardly on score 11 and outwardly on score 12 so that rib 13 rests against the lower ends of sections 18, 19, 20, 21 and 22. The blank 10 is then bent inwardly on score 15. Glue or other suitable adhesive is then applied longitudinally along the outer portions of sections 22 and 40. The blank 10 is folded inwardly on score 17 and glued strip 41 is pressed down on the outer side of sections 18 and 36 and section 31 of rib 13 is tucked under section 21. The carton is shipped this way, as shown in Fig. 5. Our carton may be formed with slight variation by folding inwardly first on score 15. The glued strip 41 may then be applied to the outer portions of sections 22, 31 and 40. The blank 10 is then folded inwardly on score 11, outwardly on score 12 and inwardly on score 17. Section 31 of rib 13 is tucked under section 27, and the glued strip 41 is pressed against the outer portions of sections 18 and 36.

When our carton is desired for use the carton is opened up by bending inwardly on scores 14 and 15. Section 37 is folded inwardly, followed next by section 38 and then by sections 36 and 40 which are now glued together to form a single section. The last section to be bent inwardly is section 39. The outer side of section 28 may have a slit 42 so as to prevent the accidental opening of section 39. It will be noted that when section or flap 37 is bent inwardly it folds into the recess formed by rib 13 and rests against rib 13. Flap 37 not having been cut down in size to provide slits 32 or 33 fits tight against the inner walls and is prevented from accidental engagement for friction grip thereon. Flaps or sections 38 and 36 and 40 being smaller fit easily within the recess. The last flap or section 39 like section 37 is of full size and fits against the inner side walls of the recess by friction grip. The carton thus formed can

stand erect without the need of extraneous means. A flap 43 extending outwardly from the glued strip 41 on section 22 provides means for the removable insertion of a napkin or the like.

- 5 5 When it is desired to have a closed top we may provide a larger blank having on its face an interrupted score 44 at the upper ends of sections 18, 19, 20, 21 and 22. Spaced above score 44 is an outwardly creased score 45. This 10 forms a rib or fold 46. The longitudinal extending scores 14, 15, 16 and 17 extend almost to lateral score 44. Unweakened spaces 65, 66, 67 and 68 are left between longitudinal scores 14, 15, 16 and 17 and interrupted lateral score 44. 15 When the blank is bent inwardly at a later time on longitudinal scores 14, 15, 16 and 17, sections 49, 50, 51, 52 and 53 are formed in rib 46. Above rib 46 and from score 45 spaced slits 54, 55, 56 and 57 extend longitudinally to the upper edge 20 of the blank, forming sections 58, 59, 60, 61 and 62. Slit 54 is cut out of the inside portion of section 58. Slits 55 and 56 are cut out of opposite side portions of section 60. Slit 57 is cut out of the inner side of section 62. Sections 25 59 and 61 are not cut away and remain at their full original size. The folding of this top portion follows the same procedure as the folding of the bottom heretofore described.

Where it is desired to have a simple closure 30 instead of a set in top formation as above described, the rib 46 may be omitted. In this type of closure two or more of the flaps may have cut out portions and tongues for inter-engagement so as to retain the top in closed position.

Having thus described our invention, we claim:

1. A carton formed of a single blank comprising a body portion having spaced longitudinal scores to form the sidewalls of the carton, one of the side walls formed by overlapping opposite edges of the body member, a rib portion formed by a pair of spaced lateral scores adjacent one end of the body member, said rib portion folded so as to contact the side walls on the inside of the carton, that portion of the rib on the top portion of the overlapping side wall being folded under the portion of the rib on the bottom portion of the underlapping side wall so as to provide a sealed leak proof connection, 10 said overlapping portions of the side walls held together by adhesive means, and a closure portion divided into a plurality of flaps by spaced longitudinal slits, said flaps adapted to fold inwardly to form a closed end for said carton. 15

2. In a carton formed of a single blank, said blank having an interrupted lateral score, a plurality of longitudinal scores extending from the upper edge of the blank and ending short of the lateral score, said lateral score interrupted short of each longitudinal score so as to leave unweakened portions between the scores so that when the blank is folded on the scores to form the side walls of the carton, holes caused by folding on the meeting places of scores are 30 prevented. 25
